UNITED STATES PATENT OFFICE

ROBERT A. SARGENT, OF MONTPELIER, OHIO, ASSIGNOR TO THE W. C. HELLER & CO.,
OF MONTPELIER, OHIO, A CORPORATION OF NEW JERSEY

DISPLAY-CABINET STRUCTURE

Application filed December 6, 1926. Serial No. 152,943.

The present invention relates to display cabinets; and its object is to provide an improved display closure for the door of a cabinet, which may be turned to closed and opened positions and may be readily demounted from the rest of the cabinet structure and as readily remounted thereon.

This and any other and more specific objects hereinafter appearing are attained by, and the invention finds preferable embodiment in, the cabinet structure hereinafter particularly described in the body of this specification and illustrated by the accompanying drawings, in which:—

Figure 1 is a face view of a cabinet, its door closure being shown in closed position;

Figure 2 is a horizontal sectional view thereof taken on line 2—2 of Figure 1, the swinging frame carrying the closure being shown in partially open position;

Figure 3 is a horizontal sectional view of the closure and said frame taken on line 3—3 of Figure 1;

Figure 4 is a vertical sectional view of upper portions of said parts, illustrating means for detachably connecting them together in turnable relation;

Figure 5 is a vertical sectional view of the same parts taken on line 5—5 of Figure 4;

Figure 6 is a front side view of said parts;

Figure 7 is a top plan view of the upper portion of said frame; and

Figure 8 is a face view of lower portions of said closure and said frame shown partially in vertical central section and illustrating means for detachably connecting said parts together in turnable relation.

In the embodiment of the invention illustrated by the accompanying drawings, the

cabinet 1 adapted to contain articles offered for sale has in its front a door 2 closable by the rectangular frame 3 hingedly mounted at 4 thereon and having a rectangular opening 5 through the frame. A closure 6 for this

opening is adapted to display samples (not shown) of the articles contained in the cabinet, as by mounting such samples on suitable hooks or retaining screw bolts 7 carried

by the closure at both sides 8, 9, thereof.

This closure is revoluble in the opening 5 of the frame 1, so that either of its sides 8 or 9 may be turned outwardly to display to view the articles carried on said sides. To effect this purpose, the closure 6 is revolvably and 55 is also removably mounted centrally of its upper and lower ends 10, 11 on the upper and lower ends 12, 13 respectively of the frame 3, and by the following means: The lower end or rail 13 of the frame 3 has a bearing 14 in which turns a spindle 15 carried by the lower end 11 of the closure 6, a ball bearing 16 preferably supporting the bottom of this spindle in said bearing. The closure 6 has a bearing 17 in its upper end 10 in which turns the lower 60 end of a pivot plunger 18 axially-movable in a bearing sleeve 19 in the upper end or rail 12 of the frame 3. The opposite end of the plunger 18 is provided with a head 18^a which 65 slidably fits within the sleeve 19. This pivot plunger is surrounded within the sleeve, by a compression spring 20 which bears between the head 18^a and an inwardly extending annular shoulder 19^a formed at the lower end of 70 said sleeve bearing. The spring 20 normally urges the plunger outwardly or upwardly so that its lower end may be withdrawn out of the bearing 17 whenever the catch 21 swingably mounted at 22 on the upper end or rail 12 of the frame 3 is turned out of engagement with the head end of this pivot plunger. When the lower end of this pivot plunger is 75 withdrawn from the closure's bearing 17, the upper end of the closure may be tilted forwardly, whereupon it may be lifted to carry 80 its spindle 15 out of the bearing 14, whenever it may be desired to remove the closure from the rest of the cabinet structure for the purpose of mounting articles on the closure for displaying the same.

The closure 6 is provided with spring catches 25, 26 on its opposite lateral edges, which engage in the keepers 30, 27 on the opposite sides 28, 29 of the frame 3 to releasably hold the closure in closed position with either side 8 or 9 outwardly.

The invention being intended to be pointed out in the claims, is not to be limited to or by details of construction of the particu- 100

lar embodiment thereof illustrated by the drawings or hereinbefore described.

I claim:

1. A device of the class described comprising a supporting frame, a bearing mounted on said frame, a pivot plunger axially slidable in said bearing with one end thereof normally projecting therefrom, a compression spring acting between said bearing and plunger for shifting said plunger axially to withdraw said projecting end, and a catch mounted on said frame swingably in a direction transverse to the axis of the pivot plunger for preventing axial movement of said plunger by said spring when said catch is in one position, and for permitting such axial movement by said spring when said catch is in another position.

2. A device of the class described comprising a supporting frame, a tubular bearing sleeve mounted on said frame, an inwardly projecting annular shoulder at one end of said sleeve, a pivot plunger axially slidable in said sleeve with one end thereof normally projecting below the end of said sleeve having said annular shoulder, a head on the other end of said pivot plunger slidably fitting within said sleeve, a compression spring surrounding said plunger within said sleeve, and bearing between said shoulder and said head for normally urging said plunger so as to withdraw said projecting end, and a catch mounted on said frame swingably in a direction transverse to the axis of the pivot plunger for engaging the head end of said plunger and retaining it within said sleeve when in one position, and for permitting said spring to shift said plunger and withdraw said projecting end when said catch is swung to another position.

3. In a structure of the character described: a cabinet having a door opening; a frame mounted therein swingably to and from a position closing said door opening, said frame having an opening therethrough and a bearing extending through one of its ends; a pivot plunger axially removable from and slidable in said bearing with one end normally projecting therefrom to operative position; a compression spring for shifting said plunger axially to withdraw said projecting end from operative position; a catch mounted on said end of said frame swingably in a plane parallel with that of the frame's swinging movement for preventing removal of the plunger from said bearing and for preventing the axial movement of the plunger from its operative position by said spring when the catch is swung to one position, but permitting said removal and said axial movement by the spring when the catch is swung to another position; a closure in the frame's opening having a socket in its end in which socket said project-

ing end of the plunger seats and about which the closure swings.

In testimony whereof I have hereunto set my hand at Montpelier, Ohio, this 29th day of November, 1926.

ROBERT A. SARGENT.
